SEWING MACHINE FRAME

Arthur N. Hale, Park Ridge, Ill., assignor to Union
Special Corporation, Chicago, Ill.

Filed Jan. 26, 1973, Ser. No. 326,971

Term of patent 14 years

Int. Cl. D15—09

U.S. Cl. D70—1

FIG. 1

FIG. 2

FIG. 3

FIG. 4

FIG.5

FIG. 1 is a front elevational view of a sewing machine frame showing my new design.

FIG. 2 is a rear elevational view of the frame of FIG. 1.

FIG. 3 is a side elevational view of the frame of FIG. 1 as seen from the right hand side of FIG. 1.

FIG. 4 is a side elevational view of the frame of FIG. 1 as seen from the left hand end of FIG. 1.

FIG. 5 is a top plan view of the frame of FIG. 1.

I claim:

The ornamental design for a sewing machine frame, as shown.
